FORMING DIE FOR INTAGLIO PRINTING MACHINE PLATES

Robert W. Bender, Kansas City, Mo., assignor to
Inter-Collegiate Press, Kansas City, Mo., a cor-
poration of Missouri

Application June 15, 1936, Serial No. 85,338

7 Claims. (Cl. 153—3)

This invention relates to forming die for intaglio printing machine plates and the primary object is to provide a specially constructed die that will form the plates after one side thereof has been engraved and so that one end of the plate will always serve as the guide end to the advantageous results set down and illustrated in my co-pending application for United States Letters Patent covering the plate holder for intaglio printing machine filed on even date herewith.

One of the important aims of this invention is to provide a die of the aforementioned character which has as an important part thereof a pair of coaxial forming members, one of which is supported by cushion springs so that after a plate is arched between the forming members, the cushion springs will yield to permit unitary movement of both forming members and the plate for the purpose of offsetting a portion of the said plate which has been projected beyond one end of the said forming members.

Another object of this invention is the provision of a forming die wherein is included a resilient maintaining means which functions to hold one end of the printing plate against a guide block so that the said end may serve as an abutment when the plate is affixed to the holding means of the intaglio printing machine.

An even further object of the present invention is the provision of a forming die having a guide block that is provided with a gauge face and an arcuate shoulder, both of which are located at one end of the printing plate so that it will be held in proper place between the forming members of the die and later provided with an offset portion respectively.

Other objects of the invention will appear during the course of the following specification referring to the accompanying drawing wherein the preferred embodiment of the invention is illustrated.

Figure 1 is a side elevation of a forming die embodying the present invention, parts being broken away for clearness.

Fig. 2 is a top plan view of the forming die with the upper forming member and connecting element entirely removed.

Fig. 3 is a cross-sectional view taken on line III—III of Fig. 2.

Fig. 4 is a plan view of the intaglio printing plate before it is acted upon by the die.

Fig. 5 is an edge view of the same, and,

Fig. 6 is an edge elevation of the printing plate showing the arched and offset condition after removal from the die.

Printing plate 8 is usually formed of sheet metal having a thickness which will readily permit the plate being arched through the employment of but very little pressure or force when operating the die contemplated by this invention.

The printing surface 10 of plate 8 is engraved as at 12 to present any suitable indicia and after the engraving operation plate 8 is acted upon by the die so that it presents a form such as that illustrated in Fig. 6. After the die acts upon the plate its body is longitudinally arched so that the engraving 12 is on the convex side of the plate and there is an offset portion 14 at one end of plate 8 which projects the end of the plate at said offset portion below the normal arcuate plane of 10 the plate. Offset portion 14 is formed from a projected portion of plate 8 when the plate is in a planar condition. Reference to Fig. 1 will readily teach one skilled in the art the manner in which the plate is acted upon.

The die comprises a shoe 16 cored as at 18 so as to present at least a pair of cavities within which rest the cushion springs 20. These cushion springs bear against the bottom of one forming member 22 and are strong enough to hold said member 22 against movement in the direction of the line of force until plate 8 is arched. The other forming member 24 is carried by an element 26 that connects the said member 24 to any suitable source of power. A guide block 28 having a gauge face 30 and an arcuate shoulder 32 provided thereon is mounted upon shoe 16 at one end of forming members 22 and 24. An anchor block 34 is carried by shoe 16 at the other end of said forming members and the maintaining spring 36 has one end thereof secured to anchor block 34 by suitable means such as a clamping strip 38 that is secured to block 34 by machine screws or analogous means 40.

Spring 36 is arched as illustrated in Fig. 1 and 35 the free end thereof frictionally bears against one end of plate 8 opposite from that end which is held against gauge face 30. Spring 36 projects upwardly and over anchor block 34 and the portion thereof adjacent the free end which 40 bears against plate 8 is extended into cavity 42 formed in block 34. A similar cavity 44 created in guide block 28 serves as means for forming gauge face and arcuate shoulder 30 and 32 respectively.

Figure 1 indicates the manner in which these two faces 30 and 32 merge along a line of meeting so that when the upper forming member 24 is moved downwardly to the position shown in dotted lines of Fig. 1, the end of plate 8 will 50 leave gauge face 30 and be turned upwardly by engagement with arcuate shoulder 32. As upper forming member 24 approaches member 22, plate 8 is arched and longitudinally contracted but spring 36 is in frictional engagement with one end 55 of plate 8 throughout the entire operation. After the plate is arched by bringing together one forming member 22 and the other forming member 24 with the plate 8 therebetween, springs 20 are compressed so that the projected end forming 60

the offset portion 14 is turned upwardly by being forced against shoulder 32.

The relation between plate 8 and cushion springs 20 is required to be such that plate 8 will arch before enough pressure is exerted to compress cushion springs 20. An abutment member 46 serves to stop the inward movement of plate 8 when it is introduced into the die and further functions as a guide for both forming members

10 22 and 24. It has been found that the end of plate 8 at the offset portion 14, will always remain a predetermined given distance from the center of engraving 12 when a die of this character is used and since engraving 12 is always placed in 15 plate 8 with regard to a center line, it is important that the distance between the center of engraving 12 and the end of plate 8 at offset portion 14 remain the same in all plates formed.

Having thus described the invention, what is 20 claimed as new and desired to be secured by Letters Patent is:

1. A forming die for printing machine plates comprising a pair of movable forming members for arching the plate; a guide block adjacent to 25 said forming members; and means for forcing one end of the plate being formed against a portion of the guide block before the members are moved toward each other to arch the plate, said forming members and plate being movable as a 30 unit after the plate is arched, to force the plate against another portion of the guide block to form an offset portion thereon.

2. A forming die for printing machine plates comprising a pair of movable forming members 35 for arching the plate; cushion springs yieldably supporting one of the forming members; a guide block adjacent to said forming members; and means for forcing one end of the plate being formed against a portion of the guide block before the other forming member is moved toward the one forming member to arch the plate, said pair of forming members and plate being movable as a unit to compress the cushion springs after 40 the forming members come together, to force the plate against another portion of the guide block to form an offset portion thereon.

3. A forming die for printing machine plates comprising a pair of movable forming members for arching the plate; cushion springs yieldably 50 supporting one of the forming members; a guide block adjacent to said forming members; and means for forcing one end of the plate being formed against a portion of the guide block before the other forming member is moved toward the one forming member to arch the plate, said pair of forming members and plate being movable as a unit to compress the cushion springs after 55 the forming members come together, to further force the plate against another portion of the guide block to form an offset portion thereon, said cushion springs exerting a force to support the said one member greater than the force required to move the other member toward the first member to arch the plate.

60 4. A forming die for printing machine plates comprising a pair of movable forming members for arching the plate; cushion springs yieldably supporting one of the forming members; a guide block at one end of the forming members having 65 a gauge face and an arcuate shoulder provided thereon; and means for maintaining one end of the plate projected beyond the forming members and in engagement with the gauge face of the

guide block before the other forming member is moved toward the one forming member to arch the plate, said cushion springs yielding after the plate is arched to cause unitary movement of the plate and both forming members to bring a portion of the plate at the projected end thereof into engagement with said shoulder to form an offset portion thereon.

5 5. A forming die for printing machine plates comprising a pair of movable forming members for arching the plate; cushion springs yieldably supporting one of the forming members; a guide block at one end of the forming members having a gauge face and an arcuate shoulder provided thereon; and means for maintaining one 10 end of the plate projected beyond the forming members and in engagement with the gauge face of the guide block before the other forming member is moved toward the one forming member to arch the plate, said cushion springs yielding after 15 the plate is arched to cause unitary movement of the plate and both forming members to bring a portion of the plate at the projected end thereof into engagement with said shoulder to form an offset portion thereon, said means for maintaining the plate against the guide block being located at the other end of said forming members and exerting pressure against the plate throughout the forming operations.

20 6. A forming die for printing machine plates comprising a pair of movable forming members for arching the plate; cushion springs yieldably supporting one of the forming members; a guide block at one end of the forming members having a gauge face and an arcuate shoulder provided 25 thereon; and means for maintaining one end of the plate projected beyond the forming members and in engagement with the gauge face of the guide block before the other forming member is moved toward the one forming member to arch 30 the plate, said cushion springs yielding after the plate is arched to cause unitary movement of the plate and both forming members to bring the projected portion of the plate at the end thereof into engagement with said shoulder to form an offset portion thereon, said means for maintaining the plate against the guide block being a 35 spring anchored at the other end of said forming members and bearing against the other end of the plate throughout the forming and offsetting operations.

40 7. A forming die for printing machine plates comprising a pair of movable forming members for arching the plate; cushion springs yieldably supporting one of the forming members; a guide 45 block at one end of the forming members having a gauge face and an arcuate shoulder provided thereon; and means for maintaining one end of the plate projected beyond the forming members and in engagement with the gauge face of the guide block as the other forming member is moved toward the one forming member to arch the plate, said cushion springs yielding after 50 the plate is arched to cause unitary movement of the plate and both forming members to bring the projected portion of the plate at the end thereof into engagement with said shoulder to form an offset portion thereon, said means for maintaining the plate against the guide block being located at the other end of said forming members in frictional engagement therewith.
